UNITED STATES PATENT OFFICE.

PHILIP M. BIONDO, OF BROOKLYN, NEW YORK.

GRAPHIC INSTRUMENT.

Application filed March 29, 1926. Serial No. 98,351.

This invention relates to graphic instruments and has for an object to provide an improved construction wherein the writing or scribing instrument may be moved to an operating position or to a protected and inoperative position.

Another object of the invention is to provide an instrument which may be used for writing wherein the writing or scribing member is readily movable from one position to another and is held firmly in place in either position, the parts being so arranged that when in one position the writing member is covered and protected against injury while in the other position it is moved to a point where it may engage the article to receive the writing.

A further object, more specifically, is to provide an instrument wherein a sliding sleeve is positioned to carry a scribing member and is mounted to slide on a tube so that when in one position the scribing member is protected by the tube and when in the other the scribing member is projecting beyond the tube ready for use.

In the accompanying drawing—

Figure 1 is a perspective view of an instrument, disclosing an embodiment of the invention, the same being shown in use.

Figure 2 is a side view of the instrument shown in Figure 1, the parts being moved to an inoperative position.

Figure 3 is a sectional view through Figure 2, approximately on line 3—3.

Figure 4 is an enlarged detail perspective view of the tube shown in Figure 2, the same embodying certain features of the invention.

Figure 5 is a perspective view of the slide shown in Figure 2, the same embodying certain features of the invention.

Referring to the accompanying drawing by numerals, 1 indicates the scribing member which is shown as a pen but it might be a pencil or sharpened piece of metal. The scribing member is mounted as hereinafter fully described on the slide 2 which is slidably mounted on a tube 3, which tube is rigidly secured to the handle 4. The slide 2 is provided with a depending looped section 5 which is adapted to be engaged by the thumb and second finger as shown in Figure 1 when the device is in use, said portion 5 acting to compel the hand to be properly positioned in respect to the instrument and to also cause the instrument to be held at a proper angle in respect to the hand. This

will have a tendency to tilt or compel a correct holding of the instrument or in fact, a correct holding of any pen or pencil. The handle 4 may be wood or any desired material and is secured to the tube 3 in any desired manner, as for instance, by having portions 6 of the tube forced into the wood. The tube 3 is formed of sheet metal and when certain portions are forced into the handle 4, a burred formation is produced which will act in a certain sense as brads for holding the parts firmly together. It is evident, however, that small nails or other securing means could be provided without departing from the spirit of the invention. The tube 3 is provided with a slot 7 for its full length except at the outer end where the slot is covered by a ring 8 soldered or otherwise rigidly secured to the tube. This ring holds the slot open at one end while the fastening means 6 holds the slot open at the opposite end as well as secures the tube to the handle. In addition, the edge 9 of ring 8 acts as an abutment or stop for the slide 2 whereby it is limited in its outward movement.

The slide 2 is preferably made from a single piece of sheet metal and is bent with an arc-shaped section 10 merging into a straight section 11 which projects through the slot 7, said straight section in turn merging into the circular or rather tubular section 12 which in turn merges into a second straight section 13 and said second straight section merges into an arc-shaped portion 14 co-acting with the section 10 for clamping the pen or other scribing member in place. It will be evident that the shape of the members 10 and 14 may be varied in order to carry different shaped scribing instruments or members, as for instance, of the shape to receive a lead pencil or a pointed metallic member. As shown in Figure 5, the arc-shaped members 10 and 14 project preferably a short distance beyond the tubular part 12 so that when the end 15 strikes the shoulder 9, members 10 and 14 will project a short distance beyond the tube 3 so that the pen or other instrument may properly function.

When the device is in use, the parts are arranged or moved until they will occupy substantially the position shown in Figure 1. When the device is not in use, the slide 2 is moved back until it assumes substantially the position shown in Figure 2, which move-

ment will cause a retraction of the instrument 1 until the same is wholly within the tube 3 and is protected thereby. This permits the instrument to be carried in a pocket or in any desired manner. The slide 2 is made of sheet metal and the parts are so sprung that the straight sections 11 and 13 press against the tube 3 at the slot 7 whereby the slide 2 will remain in any position 10 in which it is placed.

What I claim is:

1. A graphic instrument comprising a tube having a slot, a handle extending from said tubular member at one end, a stop near 15 the opposite end, a slide mounted on said tube formed with a looped radially extending portion acting as a thumb and finger grip for causing the instrument to be correctly positioned in the hand when in use, 20 and means extending from said slide projecting through said slot and acting as a scribing instrument grip.
2. A graphic instrument comprising a tubular member having a longitudinally positioned slot, a handle connected with said tubular member at one end, means at the opposite end acting as a stop, a slide formed

with a tubular portion, a looped thumb and finger grip, and a pair of pen gripping extensions, said gripping extensions projecting through said slot for gripping a pen within 30 said tubular member and said looped thumb and finger grip projecting radially from the tubular member for causing the hand to be properly positioned when using the device, said pen gripping extensions being movable into and out of said tubular member as the slide is moved.

3. A graphic instrument comprising a tube having a longitudinally positioned slot, a 40 handle extending from said tube at one end, a stop near the opposite end, a slide mounted on the tube formed with a tubular portion and a radially extending looped portion, said tubular portion being formed with inwardly 45 extending arc-shaped clamping members, said clamping members extending through said slot and positioned for clamping a scribing instrument within said tube, said radially extending portion depending an appreciable distance from the tube and acting as thumb and finger guides.

PHILIP M. BIONDO.
